LUBRICATOR FOR INTERNAL COMBUSTION ENGINES

Joseph Alvin Armitage, Caulfield, Victoria,
AustraliaApplication December 22, 1938, Serial No. 247,276
In Australia January 8, 1938

10 Claims. (Cl. 123—196)

This invention relates to an improved lubricator for internal combustion engines, and refers more particularly to lubricating devices of the type for use on automobile and like engines for automatically delivering predetermined charges or quantities of lubricating oil to the cylinders of the engine by way of the induction manifold during the starting or running of the engine.

It is well known that the cylinders of an internal combustion engine become devoid of lubricant, or practically so, after the engine has been stationary for a period sufficiently long to permit the engine to become cold, which generally speaking, usually occurs after a period of about half an hour, and that the starting of the engine from cold causes considerable wear to the cylinder walls and pistons until the engine lubricant is circulating sufficiently to reach and efficiently lubricate such parts. Many devices have been devised to automatically supply to the cylinders, by way of the induction manifold, a supply or charge of lubricant, during the starting of the engine and/or for a period after starting. Such devices automatically operate each time the engine is started without regard to the time for which the engine has been stationary, and as stated, the cylinders do not lack lubricant until the engine becomes cold or has remained stationary for a considerable period, consequently the automatic supply of lubricant to the cylinders, when restarting the engine after a short stop, is unnecessary and wasteful of lubricant, this being particularly evident in the case of automobile engines which in use are stopped and restarted for considerably varying periods.

The main object of the present invention is to provide a lubricating device for automatically supplying charges or quantities of lubricating oil to the cylinders of an internal combustion engine during the starting of the engine and/or for a period after starting, whereby the charges or quantities delivered to the engine cylinders can be accurately timed and governed according to the time elapsing between the stopping and restarting of the engine.

Another object of the invention is to provide means for automatically removing obstructions that may lodge in small orifices embodied in the lubricating device.

A further object of the invention is to provide means to prevent an overcharge of lubricating oil being delivered to the engine, should the device be overcharged with oil.

The improved lubricator according to the present invention may comprise a main chamber to

receive a supply of lubricating oil, a feed chamber beneath the main chamber and adapted to receive oil from the main chamber at a predetermined rate, a tube connected to the intake manifold of an internal combustion engine and to the main chamber above the level of oil therein, said tube extending a predetermined distance into the feed chamber, and a pipe in said chamber connected to the air to limit or determine the amount of oil to be passed into the feed chamber, the distance said tube extends into the feed chamber determining the time to elapse between the stopping and restarting of the engine at which the cylinders will receive a supply of oil from the feed chamber when the engine is restarted, while the distance said tube extends below the level of oil in the feed chamber regulates the amount of oil the engine cylinders will receive.

Starting of the engine draws the predetermined amount of oil into the engine cylinders from the feed chamber through the connecting tube, the remainder of the oil in the feed chamber being drawn back into the main chamber through the connection therebetween, at which time air is drawn through the connection to effect the removal of any obstructions that may have lodged therein.

In one embodiment of the invention where a large oil reservoir is required, the feed chamber may be located within the main chamber, the feed chamber being supplied or fed with oil at a predetermined rate from a secondary oil reservoir positioned above said feed chamber, the secondary reservoir being automatically charged with oil from the main chamber whereby the rate of supply from the secondary chamber is independent of the oil level in the main chamber. Furthermore when it is desired to prolong the time to elapse, between the stopping and restarting of the engine, at which the engine cylinders will receive a charge or quantity of oil when the engine is started, the secondary reservoir and feed chamber may be interposed by an intermediate chamber supplied with oil at a predetermined rate from the secondary reservoir, said intermediate chamber being filled to a predetermined level before the feed chamber receives a charge or quantity of oil therefrom.

In order that the invention may be more readily understood reference will now be made to the accompanying drawing illustrating practical embodiments of a lubricator according to the invention, and in which:

Figure 1 is a sectional elevation of a lubrica- 55

tor in which the feed chamber is positioned exteriorly of the main chamber and

Figure 2 is a plan view thereof with the top of the main chamber removed.

5 Figure 3 is a detail view of the parts forming the union between the lubricator and the pipe connecting with the engine.

10 Figure 4 is a sectional elevation of a lubricator having a larger reservoir in which the feed chamber is located within the main chamber.

15 Figure 5 is a sectional elevation of a modified form of lubricator as shown in Figure 4, in which means are included for providing a prolonged delay in supplying a charge of oil to the feed chamber.

20 As illustrated in Figures 1 to 3 the lubricator comprises a main chamber 6 having lugs 7 attached thereto to enable the chamber 6 to be fixed in any convenient position adjacent an internal combustion engine, the top 8 of the chamber 6 being provided with an opening through which lubricating oil can be supplied to said chamber, the opening being sealed by a screw cap 9, the chamber 6 also having a suitable oil 25 level indicator 6^a. Attached to the bottom of the chamber 6, by means of a bolt 10 and nut 11, is a feed chamber 12, air and oil tight joints being obtained by means of packing rings 13.

25 Projecting downwardly into the feed chamber 30 12 from the main chamber 6 is a drip tube 14 having a detachable end 14^b with a reduced passage 14^a therein, the passage 14^a determining the rate of flow of oil from chamber 6 into feed chamber 12. The end 14^b of the drip tube 14 35 may be covered with a gauze filter 15, the closed end of which contacts the bottom of feed chamber 12 and so assists the passing of oil back into the chamber 6 in a manner to be hereinafter described.

40 The end 14^b of the drip tube is detachable for cleaning and the inner end 14^d thereof is cone shaped. The upper portion 14^c of the drip tube has openings 16^a therein, located in a groove around which is positioned a filter gauze 15^a. Attached to said upper part 14^c is a pipe 16 which extends to a position adjacent the top 8 of the chamber 6 the top of pipe 16 being furnished with a cap 16^b.

45 The upper end of the feed chamber 12 is connected to the air by means of pipe 17 which passes up through the main chamber 6 and terminates outwardly of the top 8 of the chamber 6. The air pipe 17 permits oil to drop, at a rate determined by the drip tube, from the chamber 6 into the feed chamber 12 until the oil level reaches the lower end 17^a of said air pipe 17, at which time an air lock occurs in the upper part 50 of the chamber 12 to prevent the further flow of oil.

55 60 Extending a predetermined distance into the feed chamber 12 is the end 18^a of one leg of a U-shaped pipe 18, the end 18^b of the other leg being attached to a threaded metal sleeve 19 adapted to be connected to the inlet manifold 65 of an engine, said sleeve 19 being attached to and projecting from the bottom of the chamber 6, the end 18^a of the U-shaped pipe 18 having passageway 18^c of reduced diameter therein.

65 70 The upper end 18^d of the pipe 18 is connected, by a pipe 20, to the upper end of a closed vessel 21 located in the chamber 6, the upper end of said vessel 21 being in communication with the interior of the chamber 6 by means of a short pipe 21^a, the lower end of the vessel 21 receiving 75 oil from the chamber 6 through a short pipe 21^b

of comparatively smaller diameter than the pipe 21^a, so that should the chamber 6 be overcharged with oil, that is, filled to overflowing above the upper end 18^d of pipe 18, the surplus oil will gradually feed into vessel 21 through pipe 21^b and bring the level of oil in chamber 6 below pipe 21^a and thereby prevent such excess oil entering pipe 20 and U-shaped pipe 18 and so prevent an excess supply of oil being fed to the engine to which the lubricator is connected. 10

15 The threaded sleeve 19 is internally threaded to receive a removable nipple 22, the upper end 22^a thereof being cone-shaped and the lower end 22^b being tapered, the passageway 22^c in the nipple being of reduced diameter in order that the amount of air drawn through the lubricator will not affect the carburetion of the fuel being supplied to the engine.

20 The end 22^b of the nipple 22 is adapted to engage the splayed or bell-mouthed end 23^a of the pipe 23 connecting the lubricator to the engine, a flanged sleeve 24 positioned on the pipe 23 being held in abutment with the end 23^a of the pipe by a union nut 25 adapted to be screwed on the sleeve 19 to thereby effect the engagement of the pipe end 23^a and the end 22^b of the nipple 22. 25

25 In operation the chamber 6 is charged with a supply of lubricating oil and sealed by the screw plug 9, and oil then passes through the openings 16^a in pipe 16 to pass at the predetermined rate 30 through the passageway 14^a in the drip tube 14 into the feed chamber 12. The oil continues to pass from the chamber 6 into the feed chamber 12 until the oil level reaches the end 17^a of air pipe 17 when an air lock is formed in the chamber 12 to prevent the further flow of oil. 35

40 When the engine, to which the lubricator is connected, is started, a reduced pressure is created in the pipe 23, which draws the air from the space above the oil level in chamber 6 by way of pipe 20 vessel 21 and pipe 21^a. The reduced pressure also draws oil from the feed chamber 12 through opening 18^c in the end 18^a of the U-shaped pipe 18 to pass the oil through the pipe 23 to the engine, the amount of oil drawn into the engine being determined by the distance the end 18^a of the pipe 18 extends below the level of oil in the feed chamber 12. In view of the reduced pressure that is also created in the chamber 6, the remaining oil in chamber 12 is drawn back into the chamber 6 through the drip tube 14, the complete withdrawal of oil being assisted by the end of filter 15 which forms a guide for the last dregs of oil to creep up to the end of drip tube 14. When all the oil is drawn from the feed chamber, air entering through the pipe 17 is forcefully drawn through the drip tube 14 and through the pipe 16 to chamber 6, thereby preventing excessive frothing of oil in said chamber. During the period it takes to clear the pipe 16 of oil, air is forced through holes 16^a to remove any obstructions of foreign matter which may have collected thereabout. 45

50 The air drawn through the drip tube 14 also removes any obstructions in the passageway 14^a and causes them to fall clear of the passageway 14^a and to collect at the base of the conical end 14^d. The end 22^a of the nipple 22 in sleeve 19 also functions in a similar manner. 55

55 60 The dimensions of the openings 22^c and 18^c in the various parts of pipe 18 and connecting pipe 20 are selected so that a comparatively greater reduced pressure is obtained in the upper portion of the chamber 6 than in the feed chamber 12 in order that the charge of oil to be supplied to the engine is quickly drawn off by pipe 18 and 70 75

that the remaining oil in the feed chamber is quickly returned to chamber 6 and a strong pull of air is obtained through the drip pipe 14 when all the oil in the feed chamber has been returned 5 to the main chamber. In view of the fact that while the engine is running air is drawn through the drip tube, it will be apparent that no oil will flow into the feed chamber until the engine is stopped.

10 On the engine being stopped oil will again commence to drip into the feed chamber, and should the engine be restarted before the oil level in the feed chamber has reached the end 18^a of pipe 18, no oil will be supplied to the engine, and any 5 oil that may have been passed into the feed chamber will be returned to the main chamber.

From this it will be appreciated, that as determined by the rate of oil flow passed through the drip pipe and the amount of oil necessary in the 20 feed chamber to reach the end 18^a of pipe 18, a time period may be obtained, which must elapse before the engine, on being restarted, will be supplied with a charge of oil. Furthermore, the 25 quantity of oil to be supplied to the engine may be varied by increasing or decreasing the relative distances that the ends 18^a of pipe 18 and end 17^a of air pipe 17 extend into the feed chamber, so that a greater or less quantity of oil is supplied above the level of the pipe end 18^a.

30 The rate of supply of oil to the feed chamber 12, and time necessary for the oil to reach pipe 18^a, may be so arranged that the engine will not receive a charge of oil until it has stopped long enough to become cool or cold, when the engine 35 cylinders, on the restarting of the engine, after this predetermined period, will receive a charge of oil, consequently, a saving of lubricant is effected without detriment to the efficiency of the lubricator.

40 It is evident also that the rate of supply of oil to the feed chamber 12 may vary with differences of oil level in the main chamber 6, and although this variation is inconsiderable with lubricators of ordinary size, a different position arises when 45 it is desired to provide an oil reservoir of a larger size, as for heavy commercial vehicles, or where it is necessary to provide for recharging the lubricator at longer intervals. This difficulty is met in the embodiment illustrated in Figure 4 in which the main chamber 6 has the feed chamber 50 12 located in the interior thereof.

The feed chamber 12 is position below a secondary oil reservoir 26 connected to the feed chamber by a drip tube 14, a U-shaped pipe 18 being connected to the feed chamber and engine 55 in a similar manner to the embodiment illustrated in Figures 1 to 3, the pipe 18 being in communication with the main chamber 6 by port 20^a which may be connected to a vessel such as 21, as shown in Figure 1. The feed chamber 60 has an air inlet pipe 17, and is connected by pipe 27 with a chamber 28 located at the bottom of chamber 6, the chamber 28 being charged with oil from chamber 6 through pipe 29. A pipe 30 extending to the bottom of chamber 28 65 projects upwardly to deliver oil from said chamber 28 into the secondary reservoir 26, which is preferably positioned below the filling plug 9 so that reservoir 26 is filled with oil when the main chamber 6 is being charged.

70 When the engine is started, a charge of oil is drawn by the engine from feed chamber 12 (which has received a supply of oil through drip tube 14 from reservoir 26), the remaining oil being drawn through drip tube 14 back into reservoir 75 26, in the same manner as described with

reference to Figure 1. At the same time, oil is drawn from chamber 28, through pipe 30, to be delivered into reservoir 26. When the oil level in chamber 28 falls below the level of pipe 29, air will be expelled through pipe 29 to clear any 5 obstructions therefrom, but when all the oil, from chamber 28 and pipe 30, has been removed, a free passage of air is allowed through pipe 30 and air will then cease to be expelled through said pipe 29. 10

Pipe 27 projects a short distance below the level of oil in feed chamber 12 when it is full to ensure that enough oil will pass down pipe 27 and up through pipe 30 to give a column of oil in pipe 30 to provide a resistance sufficient to ensure a blow-back of air through pipe 29. Pipe 27 also serves as an air pipe for chamber 28, so that the chamber may be recharged with oil. The pipes 27, 30 and chamber 28, are for the purpose of transferring oil from the main chamber 20 6 to the secondary reservoir 26, therefore the rate of flow of oil from the reservoir 26 is constant and is unaffected by the oil level in chamber 6.

Illustrated in Figure 5, is a similar form of lubricator to that shown in Figure 4, in which an intermediate chamber 31 is interposed between a secondary reservoir 26 and feed chamber 12, so that oil passed at a predetermined rate from reservoir 26, must first reach a level in chamber 31 as determined by pipe 32 before oil 30 is delivered by pipe 32 into the feed chamber 12. In this manner, a prolonged delay is obtained before the feed chamber 12 receives a charge of oil for delivery to the engine. The reservoir 26 receives a supply of oil from chamber 28 in 35 a similar manner as described with reference to Figure 4, while the time delay, for the chamber 12 to receive a charge of oil, is determined by the size of chamber 31 and length of overflow pipe 32, the amount of oil to be delivered to the 40 engine by pipe 18 being determined by the distance air pipe 17 and pipe 18 extend into said feed chamber 12.

I claim:

1. An improved lubricator for internal combustion engines comprising an oil supply reservoir closed to atmosphere, and a feed chamber, means connecting the reservoir and feed chamber to supply a predetermined amount of oil at a predetermined rate to the feed chamber, an air pipe connecting the feed chamber to atmosphere and arranged in the feed chamber to limit the amount of oil to be passed into the feed chamber, and a pipe connected to the feed chamber, to the reservoir above the level 55 of oil therein, and to the intake manifold of an internal combustion engine.

2. An improved lubricator for internal combustion engines, comprising an oil supply reservoir closed to atmosphere, and a feed chamber, a drip tube connecting the reservoir and feed chamber to supply oil at a predetermined rate from the reservoir into the feed chamber, an air pipe extending into the feed chamber and arranged to determine the amount of oil to be 60 passed into the feed chamber, a pipe located in the oil reservoir and connected respectively to the intake manifold of an internal combustion engine, the feed chamber, and the upper portion of the oil reservoir above the level 65 of oil therein, said pipe extending a predetermined distance into the feed chamber to enable the engine, when started, to withdraw a portion of the oil from the feed chamber.

3. An improved lubricator for internal com- 70

- bustion engines, comprising an oil supply reservoir closed to atmosphere, a feed chamber attached to the bottom of the oil reservoir, a drip tube connecting the reservoir and feed chamber
- 5 5 to supply oil to the feed chamber, an air pipe connecting the feed chamber to atmosphere, a pipe located in the oil reservoir and connected to the intake manifold of an internal combustion engine, the feed chamber and the upper portion
- 10 10 of the oil reservoir, with means arranged between the connection of said pipe to the oil reservoir to prevent the engine receiving an excess supply of oil should the reservoir be overcharged with oil.
- 15 15. An improved lubricator for internal combustion engines, comprising an oil supply reservoir closed to atmosphere, a feed chamber, a drip tube connecting the reservoir and feed chamber to supply oil to the feed chamber, an air pipe connecting the feed chamber to atmosphere, a pipe located in the oil reservoir, said pipe being connected to the intake manifold of an internal combustion engine and the feed chamber, a closed vessel located in the oil reservoir,
- 20 20 25 said vessel communicating with said pipe, the lower end of said vessel being connected through a restricted opening with the oil in the reservoir, and with the upper end of said vessel communicating by a larger opening with the reservoir above the level of oil therein.
- 30 30. An improved lubricator for internal combustion engines, comprising an oil supply reservoir closed to atmosphere, a feed chamber, a drip tube connecting the reservoir and feed chamber, said drip tube extending into the feed chamber to near the bottom thereof, an air pipe extending into the upper part of the feed chamber to supply air thereto and to prevent a further flow of oil from the reservoir when the oil in the
- 35 35 40 feed chamber reaches the end of said air pipe, a pipe located in the oil reservoir, said pipe being connected to the intake manifold of an internal combustion engine, to the reservoir above the level of oil therein, and to the feed chamber at a predetermined point below the level of oil therein, as determined by said air pipe, to provide a measured charge of oil, which is drawn through said pipe by the reduced pressure created in the intake manifold by the operation of the engine,
- 45 45 50 55 the remaining oil in said feed chamber being returned to said oil reservoir through the said drip tube by the reduced pressure in the oil reservoir by way of the connection of the said pipe located therein.
- 60 60. An improved lubricator for internal combustion engines, comprising an oil supply reservoir closed to atmosphere, a feed chamber, a drip tube connecting the oil reservoir and feed chamber to supply oil to the feed chamber, an air pipe connecting the feed chamber to atmosphere, a U-shaped pipe located in the oil reservoir, the ends of said pipe being connected to the intake manifold of an internal combustion engine and the feed chamber respectively, the upper portion of said pipe being in communication with the oil reservoir above the level of oil therein with means arranged to prevent oil in the reservoir passing directly into said pipe, the ends of said U-shaped pipe connected to the
- 65 65 70 75 feed chamber and the intake manifold having restricted openings therein to limit the amount of air drawn through the lubricator by the engine with a larger opening connecting said pipe to the reservoir, and with the end of said drip tube arranged in the feed chamber in a detachable manner, said detachable portion having a restricted passage therein, to regulate the rate of oil flow from the oil reservoir to the feed chamber.
7. An improved lubricator for internal combustion engines, comprising a main oil supply reservoir closed to atmosphere, a secondary reservoir located within the main reservoir, means arranged to automatically supply oil to the secondary reservoir from the main reservoir, a feed chamber positioned below the secondary reservoir, means connecting the secondary reservoir and feed chamber to supply oil at a predetermined rate into the feed chamber, an air pipe connecting the feed chamber to atmosphere and arranged in the feed chamber to limit the amount of oil to be passed into the feed chamber, and a pipe connected respectively to the intake manifold of an internal combustion engine, the feed chamber and main reservoir above the level of oil therein.
8. An improved lubricator for internal combustion engines, comprising a main oil supply reservoir closed to atmosphere, a secondary reservoir located within the main reservoir, a feed chamber positioned below the secondary reservoir, means connecting the secondary reservoir and feed chamber to supply oil to the feed chamber, an air pipe connecting the feed chamber to atmosphere, a pipe connected respectively to the intake manifold of an internal combustion engine, the feed chamber and main reservoir above the level of oil therein, and means to supply oil from the main reservoir to the secondary reservoir, said means consisting in a closed chamber positioned on the bottom of the main reservoir, a restricted opening in said closed chamber for the passage of oil from said reservoir into said chamber, a pipe connecting the closed chamber with the feed chamber to supply air to said closed chamber, and a pipe connecting the closed chamber with the secondary reservoir to pass the oil in the closed chamber to said secondary reservoir.
9. An improved lubricator for internal combustion engines, comprising a main oil supply reservoir closed to atmosphere, a secondary reservoir located within the main reservoir, a feed chamber positioned below the secondary reservoir with an intermediate chamber positioned therebetween, means connecting the secondary reservoir and intermediate chamber to supply oil to the intermediate chamber and means to pass a predetermined portion of the oil passed to the intermediate chamber to the feed chamber, an air pipe connecting the feed chamber to atmosphere, a pipe connected respectively to the intake manifold of an internal combustion engine, the feed chamber and main reservoir above the level of oil therein, and means arranged to automatically supply oil to the secondary reservoir from the main reservoir.
10. An improved lubricator for internal combustion engines, comprising a main oil supply reservoir closed to atmosphere, a secondary reservoir located within the main reservoir, a feed chamber positioned below the secondary reservoir with an intermediate chamber interposed therebetween, means connecting the secondary reservoir and intermediate chamber to supply oil to the intermediate chamber and means to pass a predetermined portion of the oil passed to the intermediate chamber to the feed chamber, an air pipe connecting the feed chamber to atmosphere, a pipe connected respectively to the

the intake manifold of an internal combustion engine, the feed chamber and main reservoir above the level of oil therein and means to supply oil from the main reservoir to the secondary reservoir, said means consisting in a closed chamber positioned on the bottom of the main reservoir, a restricted opening in said closed cham-

ber for the passage of oil from said reservoir into said chamber, a pipe connecting the closed chamber with the intermediate chamber and a pipe connecting the closed chamber with the secondary reservoir to pass the oil in the closed chamber to said secondary reservoir.

JOSEPH ALVIN ARMITAGE.
